UNITED STATES PATENT OFFICE.

STEPHEN SMITH, OF PHILADELPHIA, PENNSYLVANIA, ASSIGNOR TO HORNER BROTHERS, OF SAME PLACE.

DESIGN FOR A CARPET.

SPECIFICATION forming part of Design No. 14,777, dated February 19, 1884.

Application filed January 22, 1884. Term of patent 3½ years.

To all whom it may concern:

Be it known that I, STEPHEN SMITH, of city of Philadelphia, State of Pennsylvania, have invented and produced a new and original 5 Design for Carpets, of which the following is a specification.

The nature of my design is fully represented in the accompanying photographic illustration, to which reference is made.

I claim as my invention—

The design for a carpet, as shown.

Witnesses: STEPHEN SMITH,
BENTON O. SEVERN,
WILLIAM R. SCOTT.
